UNITED STATES PATENT OFFICE.

FRANK JAGER, OF CHICAGO, ILLINOIS.

CAR-ROOF CONSTRUCTION.

1,084,638.

Specification of Letters Patent. Patented Jan. 20, 1914.

Application filed August 16, 1912. Serial No. 715,345.

To all whom it may concern:

Be it known that I, FRANK JAGER, a citizen of the United States, residing at Chicago, in the county of Cook and State of Illinois, have invented certain new and useful Improvements in Car-Roof Construction, of which the following is a specification, reference being made to the accompanying drawings.

10 My invention relates to new and useful improvements in general to roof construction and more particularly to a railway freight car roof framework.

One of the objects of my invention is the 15 provision of an improved framework for car roofs whereby the car body is more effectively braced and to provide a light and strongly braced car roof frame structure designed to resist diagonal stress and particularly adapted and conformed to support and retain metallic plates composing a car roof; another object is to simplify, lighten and cheapen car roof construction by the provision of an improved carline designed to 20 obviate the use of purlins with carlines in such connection; a further object is the provision of a carline adapted to brace the car body and car roof against strains and adapted to adequately support the roof; and to 25 this end broadly stated, my invention is to provide a well braced and durable car roof which is simple, inexpensive and positively weather-tight.

These and such other objects as may hereinafter appear or are incident to my invention I attain by means of a construction illustrated in preferred form in the accompanying drawings, wherein:

Figure 1 is a plan view of a portion of a 30 car roof embodying my invention, showing the roofing plates and running board broken away to show the arrangement and conformation of the carlines.

Figure 2 is a transverse section through 35 the car roof as shown in Figure 1.

Figure 3 is a perspective of one of the K shaped carlines.

Figures 4 and 5 are sections in the lines 40 IV-IV and V-V of Figure 1 respectively.

Figure 6 is a detail drawing showing one 45 of the ridge beams.

Figure 7 is a longitudinal section through a portion of the car siding and plates as shown in unbroken portion of Figure 1.

50 In carrying out my invention it will be seen that I show a series of carlines applied

to a car body, each carline substantially of K shape and fastened in series to the car body and to each other in such a manner as to effectually resist torsional strains, this 60 arrangement possessing such inherent structural strength as to positively brace the car body and offer an adequate support to an ordinary car roof.

The entire arrangement of the members 65 composing the frame work is designed as to render unnecessary the use of purlins commonly used with carlines in car roof construction. This in itself is an economy and also affords a light structure without in any 70 way sacrificing the necessary strength desired in this connection. The roof proper comprises a series of metallic plates secured to the non-divergent member of the carlines and the plates are arranged to have sufficient play so as to yield to any diagonal strain to the car body and roof and is adapted to take care of expansion and contraction incidental to service conditions. It will 75 also be seen that the carlines are braced longitudinally in the series by the novel arrangement of ridge beams there between affording an efficient and inexpensive construction.

While I have shown my invention applied 80 to a freight car roof, it is obvious that my improvements are applicable to other roofs and the like in analogous structures and I do not therefore wish to be understood as 85 limiting myself in this respect to the precise embodiment shown.

By a reference to the drawings illustrating my preferred embodiment it will be seen that the roof frame consists primarily of a set of ridge T bars 7, and a set of substantially K shaped carlines 8. One of the complete carlines 8 is clearly disclosed in Figure 3 and consists of two angle bars 9 and 10 of ordinary commercial shape which together constitute the complete carline 8. 90 Each angle bar has a horizontal top flange 11 and a vertical side flange 12, each carline being in line longitudinally one with the other throughout the length of the series extending between the sidings 13, and is further provided with a flat intermediate central portion 14 substantially the width of the T iron 7.

The carline member 9 is substantially straight, that is non-divergent, the other member 10 has part of its top flange 11 folded over on its vertical flange inwardly to

- ward its component member 9 at the flat portion 14. From this horizontal portion 14 both members incline downwardly toward their ends. It will be seen also that the 5 member 10 has its ends divergent from the member 9, this inclination or divergence beginning at the flat portion 14 and continuing to its extremities preferably at the angle shown. Each of the members 9 and 10 has 10 its end split between the two flanges 11 and 12 and in this way providing what I shall term lugs, the top flange in the members 9 and 10 having lugs 15 and 16 respectively, slightly turned up to a horizontal position. 15 The vertical flange at the ends of the member 9 has its lug 17 turned transversely under its top flange and outwardly from its component member, and the vertical flange at the ends of the member 10 has its lug 18 20 turned transversely outwardly but in a direction away from its top flange.

The carline 8 as shown in Figure 3 is perforated at 19 for the reception of suitable clamping elements such as rivets or bolts to 25 form the complete carline.

The car sidings are each provided with a side plate 20, to the upper face of which the lugs 15 and 16 of the carline are secured by bolts 15^a and 16^a passing through suitable 30 perforations 15^b and 16^b in each lug respectively. The transverse lug 17 of the member 9 is provided with holes 9^b, the lug bearing against the vertical side of the said plate 20, and as each of the carlines are adapted 35 to be fastened together in series at their ends, the lug 18 also provided with holes 18^b lies in a slightly different vertical plane to that of the lug 17, so that when the carlines are assembled longitudinally the car the lug 18 40 of one carline is spaced away from the plate 20 sufficiently to bear against the face of the lug 17 in the adjacent carline with the holes 9^b and 18^b registering to receive bolts 9^c. In this way the carlines are fastened to each 45 other and to the side plate 20 and siding 13.

The numeral 7 as already stated indicates the longitudinal T bar member located intermediate each carline 8, having its vertical flange 7^a cut away at its extremities and the 50 horizontal flange 7^b turned downwardly to form flanges 21 as will be seen by a reference to Figure 6. When the T bar member 7 is used in connection with the carline 8 the flanges 21 are perforated at 19^a to register with the openings 19. In fastening the 55 longitudinal members 7 to the transverse member 8, one of the flanges 21 of one T bar is centrally placed against the vertical flange 12 of the member 10 at the flat portion 14 and the flange 21 of the next T bar 60 fits against the vertical flange 12 of the member 9, the T bar being bent slightly as shown at 22 to accommodate the top flange 11 of that member. When assembled and 65 fastened by the bolts 23 passing through the

openings 19 and 19^a the flattened portions 14 and the top flange 7^b of the member 7 are all in the same plane and present an even horizontal surface, any unattached flange 21 being secured to the end plates (not shown).

The car roof proper consists of a series of metallic panels 24 extending from ridge to eaves of the car, the inner upwardly flanged ends resting on the ridge bar being protected and covered by a cover plate 30. One transverse edge of each panel 24 is flanged upwardly to form a vertical margin 25 provided with a depending lip 25^a, and the other edge is flanged upwardly and downwardly to form an outwardly bent margin 26. Preferably welded to the under side of the panel 24 and provided with a conformation 27 similar to a trough or conduit, which latter is positioned directly under the bent margin 26, is a plate 28 of substantially the same length as the panel 24.

In assembling the series of roofing members, one of the panels 24 together with its attendant plate 28 is positioned as shown in Figure 5, with the outer face of the trough 90 27 against the vertical flange 12 of one of the angle bars 9. The vertical margin 25 of the succeeding panel is placed within the rebent margin and is then fastened by the rivet 29 also passing through the free edge 95 of the plate 28 and the top flange 11 of the angle bar 9.

A cross sheath 31 is positioned over the ends of the cover plates 30 where they meet with the open upper ends of the rebent 100 margins, and in this manner effectually preventing the entrance of water at that point. The numeral 32 indicates a saddle block to which is fastened the running board 33, which saddle block is shaped to fit over the 105 cross sheath and all the roofing members given additional fastening means in the bolt 34 which passes from the saddle block through the cross sheath to the T bar.

Referring again to Figure 5 it will be noticed that I show a longitudinal lip 25^a on the flange 25 within the rebent margin 26, and this has been provided to positively insure water dripping directly from the lip into the conduit beneath, instead of seeping 115 down the vertical flange and continuing along the under side of the panel 24 into the car.

The entire construction is simple and efficient, and a roof carline as shown herein being constructed of commercial shapes may be readily and inexpensively manufactured requiring but little machining. The construction possesses substantial strength and adequate stiffness to support superposed 120 roofing members and for the transverse bracing of the car siding and plates, and yet retaining the advantage of lightness in construction.

Having thus described my invention and 130

illustrated its use what I claim as new and desire to obtain by Letters Patent is the following:—

1. A metallic roof carline comprising two members of commercial section joined together intermediate their ends, one of the members running straight across the roof from eave to eave, and the other member having its ends divergent from the straight member, in combination with roofing plates having seams located along the straight member of the carline.

2. A metal roof carline comprising two members, each member having a top flange and a vertical flange, one of the members having a portion of its top flange lapped over against its vertical flange at its central portion and with its ends divergent from the other member, and means to fasten the members together at their central portions.

3. A metal roof carline comprising two component members of angle section fastened together at their middle portions 14, one diverging at its ends from the other, each member having a top and vertical flange separated at their extremities to form lugs, the top flange lugs being substantially horizontal and the vertical flange lugs of the straight member being bent transversely outward under its top flange, and the other vertical flange lugs of the divergent member also bent transversely outward but away from its top flange substantially as described.

4. A metal roof carline comprising a member running in a straight line across the roof between the eaves thereof and a divergent member each having horizontal and vertical flanges adapted to be secured to a car frame, said divergent member having a portion of its horizontal flange folded downwardly against the central portion of its vertical flange and its ends inclined from the folded portion and adapted to be secured at its central folded portion to the vertical flange of the other member.

5. A metal roof carline comprising two members of angle iron shape joined together at their middle portions, one of the members running straight across the roof from siding to siding and the other member having its ends inclining away from the straight member, and each of said members having their top and vertical flanges split at the ends to form lugs for attachment to a car frame, the top flange lugs being bent to a horizontal position and the vertical flange lugs transversely bent outwardly.

6. In a freight car, a series of carlines each comprising two members joined together at their middle portions, and each of the mem-

bers being provided at their ends with means of attachment to a car side plate, said means including the outwardly extending transverse engaging portions 17 and 18, one 65 of the said members running substantially straight across the roof from eave to eave and the other member having its ends divergent from the straight member to form the bracing member of the carline, in combination with roofing members having seams located along straight members of the carline.

7. In a roof frame work for a car having side plates or the like, of a set of carlines 75 each comprising two component members of angle section joined together at their central portions 14, the ends of one member diverging from the center and bent away from the straight member and both having 80 their top and side flanges split in at the ends forming lugs for purpose of attachment, the top lugs 15 and 16 being horizontal and bearing on the upper face of the side plates, the side lug 17 transversely bent for attachment to the vertical side of the side plates, and the lug 18 transversely positioned to bear against the lug 17, and means for fastening the lugs 17 and 18 to the side plates 85 and to each other.

8. In a car roof framework, the combination of a series of beams spaced apart from each other and running across the roof from eave to eave and provided at their ends with means for attachment to the car body; and 95 a series of distorted members, each interposed in a substantially horizontal plane between adjacent beams and having its ends secured to the ends of one beam and its intermediate portion secured to the intermediate 100 portion of the adjacent beam, thereby forming a series of approximately horizontal trusses.

9. In a roofing for a railway freight car, the combination of a carline member fastened at its ends to the car body and running straight across the car between the eaves and further braced at its middle portion by a member of commercial section, said bracing member having its ends divergent 110 from the straight member and secured to the car body, and a roofing means adapted to rest upon and to be fastened to the said straight carline member.

In testimony whereof I have hereunto signed my name this 26th day of July, A. D. 1912, in the presence of the two subscribed witnesses.

FRANK JAGER.
